UNITED STATES PATENT OFFICE.

HENRY H. LAMPERT, OF CHICAGO, ILLINOIS.

ANCHOR FOR FLOOR SLEEPERS.

Application filed February 12, 1927. Serial No. 167,685.

The main objects of this invention are to provide improved means for supporting and anchoring floor sleepers used in concrete construction work; to provide improved means for spacing the supporting means to insure a uniform spacing of the sleepers; to provide improved fastening means for securing the sleepers to the supports; and to provide a device of this kind which combines the supporting, anchoring and spacing means in a unitary structure which is durable and comparatively inexpensive.

Illustrative embodiments of this invention are shown in the accompanying drawing, wherein,—

Fig. 1 is a vertical section of a concrete slab on which floor sleepers are anchored by means of one form of anchoring device which is shown in perspective, part of the slab being broken away for the sake of clearness.

Fig. 2 is a perspective of one of the fingers shown in Fig. 1 for fastening the sleepers to the spacer.

Fig. 3 is a view similar to Fig. 1, but showing a slightly modified form of fastening and supporting means.

Fig. 4 is a perspective of one of the wire fasteners shown in Fig. 3.

Fig. 5 is an enlarged detail in elevation of one of the folded portions of the spacer shown in Fig. 3, as it appears before insertion of the wire fastener.

In the forms shown, the improved anchors are used for supporting floor sleepers 1, which are arranged horizontally on a concrete slab 2. The sleepers are disposed in substantially parallel spaced relation to form a wooden frame structure to which the usual floor boards are nailed.

In the embodiments illustrated, the anchor comprises a flat strip of metal, of substantially uniform cross section throughout its length, which is adapted to rest upon the top of the concrete slab. Formed at regular intervals along the strip are legs which are embedded in the concrete for anchoring the device to the slab. Fastening means are secured to the leg portions and project upwardly into position for attachment to the sleepers.

In the form shown in Fig. 1, the device comprises a strip 3 having portions thereof folded upon themselves to provide a plurality of legs 4, which are arranged in pairs at regular intervals along the strip. Each leg

is bent to an L-shape to provide an upright portion 5 and a foot or anchoring portion 6. The folded portions of each leg are spaced apart slightly to provide seats 7 for L-shaped fasteners 8. To secure the fasteners against accidental lateral displacement in their seats, they may be spot welded to the upright portions 5 of the legs, as shown at 9.

The fasteners 8 project above the strip 3 to provide fingers 10, having apertures 11 to receive nails 12, for attachment to the sleepers. The fingers 8 and intermediate portions 13 of the strip form substantially U-shaped seats for the sleepers. The portions of the strip between adjacent pairs of legs provide spacers 14 for spacing the sleepers.

In the form shown in Figs. 3, 4 and 5, the device comprises a strip 15 having portions thereof folded to substantially W-shape and then bent to provide L-shaped legs 16 having upright portions 17 and foot or anchoring portions 18. If desired, the folded parts 80 of the portions 17 may be spot welded, as shown at 19.

The central parts of the legs 16 are spaced adjacent their upper ends to provide gudgeons 20, in which are hinged substantially 85 U-shaped wire fasteners 21. The ends of the fasteners 21 are bent to form eyelets 22 to receive nails 23 for attachment to the sleepers.

The portions of the strip 15, located between the legs 16, form bearing surfaces or 90 seats 24 for the sleepers. The intermediate portions of the strip form spacers 25 for spacing the sleepers.

In operation, after the concrete has been poured, and before it has set, the spacers 95 are placed on the surface of the slab with the legs embedded in the concrete. After the concrete has set, the sleepers are placed in position and nailed to the upright fingers.

Although but certain specific embodiments 100 of this invention have been herein shown and described, it will be understood that numerous details of the construction shown may be altered or omitted without departing from the spirit of this invention as defined by the 105 following claims.

I claim:

1. A device of the class described comprising a strip having a portion thereof folded upon itself to form a supporting leg 110 with opposed portions of the folded parts thereof spaced apart to provide a seat, and

fastening means supported in said seat and projecting beyond said leg for attachment to a bar resting on said strip.

2. A device of the class described comprising a strip having a portion thereof folded upon itself and projecting outwardly to one side of said strip to form a supporting leg with opposed portions of the folded parts thereof spaced apart to provide a seat, and fastening means supported in said seat and extending beyond the plane of said strip for attachment to a bar resting on said strip.

3. A device of the class described comprising a strip adapted to support a bar, said strip being folded upon itself at points spaced apart longitudinally of the strip to form a pair of spaced supporting legs, opposed portions of the folded parts of said legs being spaced apart to provide seats, and fastening means supported in said seats and having spaced fingers adapted for attachment to opposite sides of the bar.

4. A device of the class described comprising a strip folded upon itself at points spaced apart longitudinally thereof to form a pair of spaced supporting legs, opposed portions of the folded parts of said legs being spaced apart to provide grooves, and a pair of fingers supported in said grooves and projecting beyond the plane of said strip, said fingers and the intermediate portion of said strip forming a substantially U-shaped seat for a bar.

5. A device of the class described comprising a strip folded upon itself at points spaced apart longitudinally thereof to form a pair of spaced supporting legs, opposed portions of the folded parts of said legs being spaced apart to provide grooves, and a

pair of fingers supported in said grooves and projecting beyond the plane of said strip, said fingers and the intermediate portion of said strip forming a substantially U-shaped seat for a bar, said strip extending outwardly on opposite sides of said seat to provide spacers.

6. A device of the class described comprising a strip having a portion thereof folded upon itself to form a supporting leg with opposed portions of the folded parts thereof spaced apart to provide a seat, said leg having a portion bent transversely thereto to form a foot, and fastening means supported in said seat and projecting beyond said leg for attachment to a bar resting on said strip.

7. A device of the class described comprising a strip adapted to support bars, said strip being folded upon itself at points spaced apart longitudinally of the strip to form supporting legs, opposed portions of the folded parts of said legs being spaced apart to provide seats, and fastening means supported in said seats and adapted for attachment to the bars, the portions of the strip located between said legs forming spacers for spacing apart the bars.

8. In a device of the class described, the combination with a concrete slab, of an anchor for floor sleepers comprising a substantially flat strip resting on the surface of the slab, a plurality of pairs of depending legs formed on said strip and embedded in the slab, and fingers mounted on said legs and projecting above said strip for attachment to sleepers resting on said strip.

Signed at Chicago this 10th day of Feb., 1927.

HENRY H. LAMPERT.
